UNITED STATES PATENT OFFICE.

JOHN WALDHEIM, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

Application filed September 9, 1920, Serial No. 409,096.

To all whom it may concern:

Be it known that I, JOHN WALDHEIM, a citizen of the United States, residing in Elizabeth, in the county of Union and State of New Jersey, have invented certain new and useful Improvements in Combined Typewriting and Computing Machines, of which the following is a specification.

This invention relates to combined typewriting and computing machines, and especially to the kind known as the Underwood bookkeeping machines disclosed in the patent to Frederick A. Hart, No. 1,176,364, of March 21, 1916, in which the numeral-keys set digit or indexing pins, the values of which may be run into one or more registers. The digit pins are usually mounted upon computing bars, of which there is one for each denominational position. These bars are individually set as the typewriter-carriage passes through the computing zone.

The invention may be used in connection with mechanism disclosed in my co-pending application, No. 359,931, filed February 19, 1920 (now Patent No. 1,403,361, dated January 10, 1922), in which there is shown a single denomination-selecting connection to all the computing bars; the connection comprising a sub-carriage which moves a set of intermediate elements over the indexing pins and into effective relation with key-operated pin-setting bars. The intermediate elements are selectively depressed to set the indexing pins for a computation.

A feature of the present invention is the provision of means to render effective one or more of a plurality of registers automatically at the movement of the typewriter-carriage. To this end, there is provided a set of intermediate pin-setting elements for each totalizer, each set being supported upon an individual carrier, the carriers being slidably mounted on the sub-carriage which is operable by the typewriter-carriage, so that the sets of intermediate pin-setting elements may be moved into and out of effective relation with the pin-setting bars. As the typewriter-carriage feeds through the computing zone, the sub-carriage is moved rightwardly in the opposite direction step by step to position the pin-setting elements.

A selector may be provided for each register, the selectors being mounted on the typewriter-carriage, and each being effective to

set one of a set of register-selecting plates; 55 each of the latter being associated with one of the pin-carriers. The sub-carriage may be picked up at intervals by adjustable devices on the typewriter carriage.

When the typewriter carriage is in the 60 first or highest denominational position in the computing zone, the intermediate setting elements stand in register with the indexing pins on the computing bars of highest denominational order. If a numeral-key is 65 now operated, the indexing pin corresponding to the key is set by the corresponding bar or linkage, by means of said intermediate setting element.

The registers may be rendered effective 70 individually or simultaneously by the various selectors on the typewriter carriage.

Other features and advantages will hereinafter appear.

In the accompanying drawings, 75

Figure 1 is a sectional side elevation of the machine, showing the invention applied thereto.

Figure 2 is a rear view of the machine, some of the parts being broken away to show 80 the interior structure.

Figure 3 is a fragmentary top plan view of the machine, the section being taken on the line 3—3 of Figure 1.

Figure 4 is a perspective view of the sub-carriage and the pin-carriers thereon, the parts being in their normal positions.

Figure 5 is a detail view of a selector for rendering all of the totalizers effective simultaneously.

Figure 6 is a vertical section through one of the pin-carriers, showing an intermediate pin thereon.

Figure 7 is a fragmentary side view, showing a pin-carrier in its effective position and 95 an indexing pin being set on a computing bar.

Numerals 10 and alphabet-keys 11, when depressed, operate key-levers 12 and 13, respectively, to rock bell-cranks 14 to 100 swing type-bars 15 to print with types 16 thereon, against the front side of a platen 17, rotatably mounted in a carriage 18. The carriage travels on rails 20 and 21 secured to the main frame 22, and is urged from 105 right to left of the machine by a spring-drum 23 connected in the usual way to the right-hand end of said carriage by a strap

24, so that the carriage may be fed at each type stroke. The type-bars are provided with heels 25 to move a curved universal bar 26 rearwardly to vibrate a loose dog 27 and a fixed dog 28, carried by a pivoted dog-rocker 30, between the teeth of an escape-
ment wheel 31, the latter having the usual one-way pawl driving connection (not shown) with a pinion 32 meshing with a feed-rack 33 pivoted on the carriage 18.

The digits of a number, as they are typed in the various denominational positions of a column while the carriage traverses a computing zone, may be set up on computing elements or bars 34, prior to running the number into dial-wheels 35 of a register 36, in a manner hereinafter described, the number on the dial-wheels being visible through a sight opening 37. To set up the digits, each numeral-key-lever 12 has pivoted thereon a plunger 38 which, as the key-lever is depressed, engages with an arm 40 on a rock-shaft 41 to operate the latter, there being nine rock-shafts, one for each numeral-key. When a rock-shaft 41 is operated, a corresponding one of a series of pin-setting elements or bars 42 is depressed by suitable linkages, as clearly shown and described in the Hart patent, herein referred to. The downward movement of the pin-setting bar 42 is effective, when the carriage is in a computing zone, to set the corresponding one of a series of indexing devices or pins 43 on one of the computing bars 34, by means of intermediate setting devices or pins 44 on a sub-carriage 45, which travels back and forth on guide-rails or bars 45*. The indexing pins 43 on each computing bar have values from "1" to "9", inclusive, corresponding to the values of the pin-setting bars 42.

It will be seen by inspection of Figures 2 and 3 that there are two registers or totalizers herein illustrated, each totalizer comprising a set of computing bars 34 arranged side by side, in descending denominational order, from left to right (Figure 4), or from right to left of the machine as seen in Figure 2, which, it will be remembered, is a rear view of the machine. Each computing bar 34 is provided with a set of nine indexing pins 43 having values from "1" to "9," inclusive. Each register has associated therewith an intermediate carrier or support 46, for the intermediate setting elements 44 which are carried thereby, Figures 4 and 6, and held in their normal upper positions by springs 47, as indicated in Figure 6. The carriers 46 are slidingly mounted on the sub-carriage 45 and each carrier occupies a position indicated in Figure 3, where the intermediate setting pins 44 are to one side of the computing bar 34 of highest denominational order. The intermediate setting pins are also normally each behind its associated pin-setting bar 42, so that when the carriage

is out of a computing zone, the numeral-keys may be actuated without disturbing the intermediate setting pins 44.

As the carriage approaches a computing zone, the registers may be separately or collectively selected by suitable selectors 50, 51 and 52 (Figures 1, 2 and 5), which may be mounted on the usual tabulator-stop-bar 53 carried by the typewriting-carriage, to operate register-selecting connections. Each register-selecting connection may comprise a plunger 54 having at its upper end a cam 55 to be engaged by one of the selectors to depress the plunger 54 against the tension of return-springs 56. The plunger 54 is connected to rock a bell-crank 57 about its fixed pivot 58 to draw a link 60 rearwardly.

The forward end of the link 60 is connected to an arm 61 secured to a shaft 62, to rock the latter to swing upwardly a register-rendering device or selector-plate 63 from its ineffective position (Figure 1) into the path of a downwardly-projecting stud 64 on the intermediate pin-carrier 46. A stop 65 may be provided to arrest the register selector-plate in its normal position. After the selector-plate has been rendered effective, the sub-carriage 45 is automatically moved leftwardly or advanced toward the computing bars 34 (Figure 2) by mechanism hereinafter described. The stud 64 consequently rides up on a cam 66 of the selector-plate to move the carrier 46 forwardly against the tension of a spring 59 to bring the intermediate pins 44 into register with the pin-setting bars or setting elements 42. The carrier 46, at the same time, is also moved laterally, as the sub-carriage advances, to bring the intermediate setting pins 44 into effective relation with the set of indexing pins 43 on the first computing bar 34 the typewriter-carriage traverses the computing zone, the intermediate pins are carried into effective relation with the indexing pins 43 on the successive computing bars. The intermediate pin-carrier 46 is held at this time, in its forward effective position by a dwell 67 of the selector-plate 63 over which the pin 64 rides, while the selector on the typewriter-carriage engages a dwell 68 on the register-selecting plunger 54 to maintain the selector-plate 63 effective so as to remain in engagement with the pin 64 as the typewriter-carriage traverses the computing zone.

To operate the sub-carriage 45 to carry the intermediate setting pins 44 into register with the indexing pins 43, there may be provided adjacent to the selectors 50, 51 and 52, pick-up devices 69 on the stop-bar 53. The pick-up devices may engage, one at a time a pick-up hook 70 to move the latter rightwardly in Figure 2, to swing an operating lever 71 about a fixed pivot 72 and against the tension of a return-spring 73. The op-

erating lever 71 may be provided at its lower end with a gear-sector or rack 74 meshing with a gear-wheel 75 to rotate a shaft 76 supported in a fixed bearing 77. The shaft 76 extends inwardly from the rear of the machine and has secured thereto at its inner end a gear wheel 78 meshing with a rack 80 secured to the sub-carriage 45, to move the latter leftwardly in Figure 2, to bring the intermediate setting pins 44 step by step into effective relation with the indexing pins 43 of the computing bars 34.

The pick-up devices 69 may be integral with column stops 81 of the regular decimal tabulator of the Underwood bookkeeping machine; said decimal tabulator comprising a plurality of keys 82 arranged in denominational order, each key, when depressed, being effective to raise a plunger or counter stop 83 into the path of the column stops 81 to rapidly position the carriage in a pre-selected denominational position of a column. It will be seen (Figure 1) that the selectors 50 and 51 are cut away sufficiently to clear the counter stops 83 when they are operated.

Since the intermediate setting pins 44 normally occupy the spaces between the pin-setting linkages 42, the intermediate pins 44 of a non-selected register moves idly over the computing bars 34 when the sub-carriage 45 is picked up to travel with the typewriter or main carriage 18.

After the last digit is typed in a column, the carriage passes out of the computing zone, and the pick-up mechanism, including the pick-up hook 70, is released from the selector by means of a pin 84 on the pick-up hook which engages with a cam 85 as the carriage moves rightwardly (Figure 2). The spring 73 then becomes effective to operate the lever 71 to restore the sub-carriage 45 to its normal position, Figure 3. When the carriage 18 leaves the computing zone, the selector moves out of engagement with the register-selecting plunger 54 and the plunger is restored by the return spring 56; consequently, the selector plate 63, which is connected to the plunger 54, is also restored to its normal position against the stop 65 (Figure 1).

It will be understood that the selectors 50 and 51 may be of different lengths, as shown in Figure 1, so as to actuate one train of register-selecting mechanism at a time. It should also be understood that the carriage may be provided with a selector, as shown in Figure 5, to actuate all of the trains of register-selecting mechanisms, so as to render all of the registers effective simultaneously. From this, it will be understood that the number being typed, as the carriage traverses the computing zone, may be set up by means of the indexing pins 43 of the computing bars. The number may

then be run into dial-wheels of one or more registers.

The set-up number may be run into the register by the usual general operator 86 having a cross-bar 87 to engage the lower ends of the set indexing pins 43 to drive the computing bars 34 forwardly and operate the dial-wheels 35, by means of racks and pinions 88 and 89 on the computing bars and dial-wheels, respectively. The general operator 86 may be actuated by an operating handle 90, which, when pulled forwardly (Figure 1), rocks a shaft 90^a. The rock-shaft 90^a may have secured thereto two gear sectors 91, one at each end, to rotate pinions 92, each pinion meshing with a rack 93 forming part of the general operator 86 to drive the general operator forwardly. The usual tens-carrying mechanism, as shown in the above-mentioned Hart patent, may be provided for the dial-wheels. The computing bars may be restored to their normal positions by the cross-bar 87 of the general operator on the return stroke thereof, said cross-bar engaging, for this purpose, with lugs or projections 94 on the computing bars 34.

The set indexing pins 43 may be restored to their normal positions by a pin-restoring platform 95, which is moved upwardly toward the computing bars 34 to push the pins upwardly thereon during the latter part of the return stroke of the general operator 86 in the usual way.

From the foregoing, it will be understood that the intermediate setting pins 44 normally occupy ineffective positions, that they are moved collectively in one direction, laterally by the pick-up mechanism including the hook 70 which is engaged by the main carriage 18 as the latter enters the computing zone, and that the intermediate setting pins are brought into the planes of the various sets of indexing pins 43 on the computing bars as the carriage traverses the computing zone. It will also be understood that the intermediate setting pins 44 are moved in a second direction to bring them into the planes of the key-operated pin-setting bars 42, that this second movement of the pins is caused by the register-selecting plate or register-rendering element 63, and that the intermediate setting pins 44 are movable individually in a third direction by the key-operated pin-setting linkages including the setting bars 42 to set the indexing pins on the computing bars.

It will further be seen that in order to facilitate the lateral and forward movement of each set of intermediate setting pins 44, each set is mounted on a carrier 46, the various carriers being in the form of slides, so that they may be moved on the carriage 45, which is subordinate to the main carriage 18; the slides being movable

- forwardly by the register-selecting plates or cam-plates 63, and laterally by means of the sub-carriage 45.
- Variations may be resorted to within the scope of the invention, and portions of the improvements may be used without others.
- Having thus described my invention, I claim:
1. In a computing machine, the combination of computing elements, a set of indexing devices on each computing element, setting elements, intermediate setting devices, a support for the intermediate setting devices, means to move said support in one direction to bring said indexing devices into register with the setting elements, and means to cause said support to travel in another direction to bring the intermediate setting devices into register with each set of indexing devices successively.
2. In a computing machine, the combination of computing elements, a set of indexing devices on each computing element, setting elements, intermediate setting devices, a support for the intermediate setting devices, a carriage for said support, means to shift said support relatively to said carriage to bring said intermediate setting devices into register with the setting elements, and means to cause said carriage and said support to travel crosswise of the computing elements to bring the intermediate setting devices into register with each set of indexing devices successively.
3. In a combined typewriting and computing machine, the combination of a carriage, computing elements, a set of indexing devices on each computing element, key-operated setting elements, intermediate setting devices, a support for the intermediate setting devices, normally ineffective means, means to render the latter effective so that said support may be shifted to bring said intermediate setting devices into register with the setting elements, and means operable by said carriage to cause said support to travel cross-wise of the computing elements to bring the intermediate setting devices into register with each set of indexing devices successively as the carriage traverses a computing zone.
4. In a computing machine, the combination of computing elements, a set of indexing devices on each computing element, setting elements, intermediate setting devices, a support for the intermediate setting devices, a carriage for said support, normally ineffective means, means to render the latter effective so that said support may be shifted thereby relatively to the carriage to bring the intermediate setting devices into register with the setting elements, and means to cause said carriage and said support to travel crosswise of the computing elements to bring the intermediate setting devices into register with each set of indexing devices successively.
5. In a combined typewriting and computing machine, the combination of a carriage, computing elements, a set of indexing devices on each computing element, the indexing devices of the various computing elements forming rows, setting elements, one in register with each row of indexing devices, intermediate setting devices, a support therefor, means to move said support laterally step by step, to bring the intermediate setting devices into effective relation with the various sets of indexing devices, and means settable by the carriage to move said support crosswise of the lateral movement thereof to bring said intermediate setting devices into effective relation with said setting elements.
6. In a combined typewriting and computing machine, the combination of a carriage, computing elements, a set of indexing devices of each computing element, setting elements, intermediate setting devices, a carrier for the intermediate setting devices, a sub-carriage, means engaged by said carriage to move said sub-carriage as the carriage traverses a computing zone, means to render said carrier effective to bring the intermediate setting devices into the planes of the setting elements, and means to retain the carrier in its effective position on the sub-carriage while the carriage traverses the computing zone.
7. In a combined typewriting and computing machine, the combination of a carriage, a plurality of registers, each register comprising computing elements, a set of indexing devices on each computing element, a sub-carriage, a plurality of sets of intermediate setting devices, one set associated with each register, a plurality of carriers, one for each set of intermediate setting devices, and register-selecting connections, each connection comprising a settable member which may be rendered effective automatically, the settable members being associated with the carriers, the effective settable members causing the associated carriers to remain in their effective positions while traveling with the sub-carriage as the carriage traverses a computing zone.
8. In a computing machine, the combination of computing elements, a set of indexing pins on each computing element, key-operated setting linkages, intermediate setting pins, a support for the intermediate setting pins, means to move the support in one direction to bring said intermediate setting pins into register with the setting linkages, and means to cause said support to travel in another direction to bring the intermediate setting pins into register with each set of indexing pins successively.
9. In a combined typewriting and com-

puting machine, the combination of a carriage, computing bars, a set of indexing pins on each computing bar, setting linkages, intermediate setting pins, a support for the intermediate setting pins, a sub-carriage to carry said support, means to shift said support relatively to said sub-carriage to bring said intermediate setting pins into register with the setting linkages, and means actuatable by said carriage to cause said sub-carriage and said support to travel crosswise of the computing bars to bring the intermediate setting pins into register with each set of indexing pins successively as the carriage traverses a computing zone.

10. In a combined typewriting and computing machine, the combination of a carriage, computing bars, a set of indexing pins on each computing bar, setting linkages, intermediate setting pins, a carrier for the intermediate setting pins, a normally ineffective cam, means to render said cam effective so that said carrier may be shifted thereby to bring said intermediate setting pins into register with the setting linkages, and means to cause said carrier to travel crosswise of the computing bars to bring the intermediate setting pins into register with each set of indexing pins successively as the carriage traverses a computing zone.

11. In a combined typewriting and computing machine, the combination of a carriage, computing elements, a set of indexing devices on each computing element, setting elements, intermediate setting devices, a support for the intermediate setting devices, a sub-carriage by which said support is carried, a normally ineffective cam-member, means to render the latter effective so that said support may be shifted thereby relatively to the sub-carriage to bring the intermediate setting devices into register with the setting elements, and a connection between said carriage and said sub-carriage to cause said sub-carriage and said support to travel crosswise of the computing elements to bring the intermediate setting devices into register with each set of indexing devices successively as the carriage traverse a computing zone.

12. In a combined typewriting and computing machine, the combination of a carriage, a plurality of registers, each register comprising computing elements, a set of indexing devices on each computing element, setting elements, each register having associated therewith a set of intermediate setting devices, a support for each set of intermediate setting devices, register-rendering devices, means to selectively set the register-rendering devices, each register-rendering device when set causing the associated support to move the intermediate setting devices into register with the setting elements, and means to cause said support to

travel crosswise of the computing elements to bring the intermediate setting devices into register with each set of indexing devices successively as the carriage traverses a computing zone.

13. In a combined typewriting and computing machine, the combination of a carriage, a plurality of registers, each register comprising a set of computing elements, each computing element comprising a set of indexing devices, key-operated setting elements, a set of intermediate setting devices for each register, a plurality of supports, one for each set of setting devices, pick-up means to be engaged by the carriage to feed the supports to bring the setting devices on each support into the planes of the indexing devices on the computing elements as the carriage traverses a computing zone, and selectively settable members to cause the supports to move in another direction to bring the intermediate setting devices into the planes of the setting elements.

14. In a combined typewriting and computing machine, the combination of a carriage, a plurality of registers, each register comprising computing elements, a set of indexing devices on each computing element, key-operated setting elements, a sub-carriage, a plurality of supports on said sub-carriage, a set of intermediate setting devices on each support, pick-up means to be engaged by the carriage to move said sub-carriage and said supports to bring the intermediate setting devices into the planes of the indexing devices, and register-selecting connections, one for each register, each connection comprising a register-rendering element associated with one of the supports to cause the associated support to move in another direction to bring the intermediate setting devices into the planes of the setting elements.

15. In a combined typewriting and computing machine, the combination of a carriage, a plurality of registers, each register comprising computing bars, a set of indexing pins on each computing bar, pin-setting linkages, a sub-carriage, a plurality of slides on said sub-carriage, a set of intermediate setting pins on each slide, pick-up means to be engaged by the carriage to move said sub-carriage and said slides to bring the intermediate setting pins into the planes of the indexing pins, register-selecting connections, one for each register, each connection comprising a plunger, selectors on the carriage to actuate the plungers, and cam-plates, one associated with each slide and settable by the plungers to cause the associated slide to move in another direction to bring the intermediate setting pins into the planes of the pin-setting linkages.

16. In a combined typewriting and computing machine, the combination of a carriage, computing elements, a set of indexing

devices on each computing element, setting elements, intermediate setting devices, pick-up means to be engaged by the carriage to move the intermediate setting devices into the planes of the various sets of indexing devices, and means to move said intermediate setting devices in another direction into the planes of the setting elements.

17. In a computing machine, the combination of a register comprising computing elements, each computing element having a set of indexing devices, key-operated setting elements, a set of normally ineffective intermediate setting devices to be interposed between the setting elements and the indexing

devices, means to move said intermediate setting devices collectively in one direction into range of the computing elements, and means to cause the set of intermediate setting devices to move collectively in a second direction into range of the indexing devices and the key-operated setting elements, said intermediate setting devices being movable individually in a third direction by the key-operated setting elements to set the indexing devices.

JOHN WALDHEIM.
